(57) **CLAIM**

The ornamental design for a mobile phone holder as shown and described.

DESCRIPTION

FIG. 1 is a front, left and top perspective view of a mobile phone holder showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another perspective view showing a mobile phone being held by the mobile phone holder;

FIG. 10 is another front, left and top perspective view showing the clamps in a contracted position;

FIG. 11 is an enlarged detail view of a circled portion 11 of FIG. 1; and,

FIG. 12 is an enlarged detail view of a circled portion 12 of FIG. 3.

The broken lines depict portions of the mobile phone holder that form no part of the claimed design. The broken lines showing the mobile phone in FIG. 9 depict environment that forms no part of the claimed design.

1 Claim, 12 Drawing Sheets
